UNITED STATES PATENT OFFICE.

SPENCER OTIS, OF CHICAGO, ILLINOIS, ASSIGNOR TO NATIONAL COAL DUMP CAR COMPANY, OF SOUTH DAKOTA, OF RAPID CITY, SOUTH DAKOTA AND CHICAGO, ILLINOIS, A CORPORATION OF SOUTH DAKOTA.

DUMP-CAR.

SPECIFICATION forming part of Letters Patent No. 739,913, dated September 29, 1903.

Application filed February 9, 1903. Serial No. 142,482. (No model.)

To all whom it may concern:

Be it known that I, SPENCER OTIS, a citizen of the United States, residing at Chicago, Illinois, have invented certain new and useful 5 Improvements in Dump-Cars, of which the following is a specification.

This invention relates to that class of cars known as "dump-cars"—that is, cars provided with a supporting frame portion and a dumping bottom portion through which loose bulky freight, such as coal and similar elements, may be easily discharged—and particularly to the means by which the dumping bottom portions are held in closed position in connection with the supporting frame portion, all of which will more fully hereinafter appear.

The principal object of this invention is to provide a simple, economical, and efficient 10 bottom dumping car.

A further object of the invention is to provide a dump-car having drop or dumping bottoms with simple, economical, and efficient mechanism by which the door is held in position and sealed when the parts are in closed position, all of which will more fully herein-after appear.

The invention consists principally in a dumping bottom car in which there are combined a supporting frame portion, dumping bottom portions forming a flat floor of the car and provided with a groove or grooves at or near its free edges, and depending tongues in the frame of the car arranged to engage the 15 grooves in the edges of the car-door, so as to help position and seal the joint between the same, substantially as hereinafter set forth.

The invention consists, further and finally, in the features, combinations, and details 20 of construction hereinafter described and claimed.

In the accompanying drawings, Figure 1 is a transverse vertical sectional elevation of a dump-car as it appears when constructed in 25 accordance with these improvements; Fig. 2, a plan view of a section of the car-bottom looking at it from above; Fig. 3, a sectional elevation of a portion of the car, taken on line 3 of Fig. 2 looking in the direction of the 30 arrow; and Fig. 4 a detail plan view of a

of the doors which forms the dumping bottom portion of the car.

In illustrating and describing these improvements I have only illustrated and will describe that which I consider to be new, 55 taken in connection with so much as is old as will properly disclose the invention to others and enable those skilled in the art to practice the same, leaving out of consideration other and well-known mechanisms, which if 60 set forth herein would only tend to confusion, prolixity, and ambiguity.

In constructing a car in accordance with these improvements I make a supporting-framework having a plurality of center sills 65 a, to which the usual draft-timber b may be secured, a plurality of deck-beams c, transversely arranged, and side and end doors d and e, extending upwardly from such framework.

To assist in carrying the load, as well as in automatically discharging the same when the desired bulky freight is being transported, I make a bottom dumping portion formed of a plurality of swinging doors f, pivotally secured at their inner edges to the framework, preferably the center sills, at each side of the longitudinal center of the car, so that they swing from the side boards downwardly and inwardly to discharge the load outside of the 70 car-tracks, all of which is desirable in many cases.

It is often necessary to have means by which these doors may be positioned when in their closed position and the joint between such doors and the car-frame sealed, so as to prevent the leakage of fine materials, such as grain, sand, or the like. In order to provide such means, each of such doors or swinging portion is provided with a groove or grooves 85 g on the three free edges thereof—that is, the front and both side edges—while the rear portion of such door is provided with an upwardly-extending tongue h. The longitudinal central portion of the car is provided with an inverted-V-shaped portion i, forming a cap and covering for the center sills and a joint between the pivoted ends of the door and such center sills, the inclined sides of which are arranged so as to be at the same angle at 90 95 100

which the doors are when in their open position, all of which tends to effectually discharge the load. The lower edges of this inverted-V-shaped portion are grooved, as at 7, 5 so that the upwardly-extending tongues or flanges on the door may operate in the same, all of which tends to seal the joint between the V-shaped portion and the rear edge of the door and prevent the leakage of material 10 therebetween.

To assist in positioning the door, as well as forming a sealing-joint between the door and the car-frame, each of the deck-beams is provided with a channel-beam *k*, forming a cap 15 therefor, as shown particularly in Fig. 2, and straddling the same so that the depending flanges thereof may rest in the grooves in the free lateral edges of the swinging doors or bottom portions, thereby positioning the 20 same as well as assisting in sealing the joint between the doors and the car-frame.

To open and close the swinging doors or bottom portions, each side of the car is provided with a rock-shaft *l*, and each rock-shaft 25 has a plurality of chains *n*, engaging therewith and with the outer free ends of the door so that as such rock-shafts are rotated in one direction the chains are wound therearound and the doors closed, and when such rock- 30 shafts are rotated or permitted to wind in the opposite direction the chains are unwound and the doors allowed to drop to their dumping position.

I claim—

35 1. In a car of the class described, the combination of a supporting frame portion, dumping bottom portions forming a flat floor of the car and provided with a groove or grooves at or near its free edges, and depending 40 tongues in the frame of the car arranged to engage the grooves in the edges of the car-door so as to help position and seal the joint between the same, substantially as described.

2. In a car of the class described, the combination of a supporting-framework, a plurality of dumping bottom portions pivotally 45 secured to each side of the longitudinal center of the car at their inner edges and provided with a groove or grooves around three 50 free edges of such doors, and depending tongue mechanism on the car-frame arranged to engage the groove mechanism of the door to assist in positioning such door and sealing the joint between it and the frame, substantially as described.

55 3. In a car of the class described, the combination of a supporting-frame provided with upwardly-extending side and end boards, a dumping bottom portion formed of a plurality of swinging doors arranged along each side and longitudinally of the car pivoted at

their inner edges to the framework of the car and provided with a groove or grooves at or near the three free edges of such door and an upwardly-extending tongue at or near their inner edges, an A-shaped cap arranged longitudinally of the car-frame so as to span the longitudinal center thereof above the dumping bottom portions at their inner edges and provided with a groove or grooves in which the upwardly-extending tongues of the swinging bottom portions operate, and depending tongue mechanism engaging with the grooves in the car-doors to assist in positioning such doors and in sealing the joint between the same and the frame of the car, substantially as described.

4. In a car of the class described, the combination of a supporting-frame provided with upwardly-extending side and end boards, a dumping bottom portion formed of a plurality of swinging doors arranged along each side and longitudinally of the car pivoted at their inner edges to the framework of the car and provided with a groove or grooves at or near the three free edges of such door and an upwardly-extending tongue at or near their inner edges, an A-shaped cap arranged longitudinally of the car-frame so as to span the longitudinal center thereof above the dumping bottom portions at their inner edges and provided with a groove or grooves in which the upwardly-extending tongues of the swinging bottom portions operate, depending tongue mechanism engaging with the grooves in the car-doors to assist in positioning such doors and in sealing the joint between the same and the frame of the car, substantially as described.

5. In a car of the class described, the combination of a supporting-framework provided with center sills transverse deck-beams and vertical side and end boards, a dumping bottom portion formed of a plurality of swinging doors arranged between the transverse deck-beams at each side of the longitudinal center of the car and pivoted to the frame thereof at their inner edges and provided with a groove or grooves at or near their free edges, and a plurality of channel-beams straddling the transverse deck-beams of the car with their lower depending edges engaging the grooves in the swinging doors of the bottom portion to assist in positioning the same and in sealing the joint between such swinging doors and the car-frame, substantially as described.

SPENCER OTIS.
